WILLIAM MILLER, OF AMESBURY, MASSACHUSETTS, ASSIGNOR TO ROBERT H. HILLS
AND WILLIAM E. BIDDLE, BOTH OF AMESBURY, MASSACHUSETTS.

LOCK-JOINT.

1,119,097.

Specification of Letters Patent.

Patented Dec. 1, 1914.

Application filed June 25, 1913. Serial No. 775,659.

To all whom it may concern:

Be it known that I, WILLIAM MILLER, a citizen of the United States, residing at Amesbury, in the county of Essex and State of Massachusetts, have invented an Improvement in Lock-Joints, of which the following is a specification.

This invention relates particularly to lock hinges, or hinged supports for automobile wind-shields, and has for its object to provide a form of frictional lock for a device of this character, which is adapted to be easily locked by a thumb-screw, so that use of a wrench is unnecessary, and which is of simple and durable construction, so that it is inexpensive to manufacture, as compared with prior devices for this purpose, and is unlikely to get out of order. I accomplish these objects by the means shown in the accompanying drawing, in which,

Figure 1 is a front elevation of a wind-shield in which a device embodying my invention is employed. Figs. 2 and 3 are views of opposite ends of the device. Fig. 4 is a central cross-section on the line 4—4 of Fig. 3. Fig. 5 is a detail end view of the device. Fig. 6 is a detail view thereof, partly in plan and partly in section, and, Fig. 7 is a detail view showing the various parts of the device disassembled.

In the drawing *a*, *a*, indicate the ordinary standards which are mounted in the automobile-body and which support the wind-shield *b* at their upper ends, a jointed connection being provided between each standard and the shield which constitutes the subject of my invention, and, as the connections are identical, except that they are made as rights and lefts, a description of one will suffice.

The jointed connection, or support which constitutes the subject of my invention comprises a fixed member *c* which is mounted on the upper end of the standard *a*, and a swinging member *d*, to which the wind-shield is attached. Said member *d* is provided with a cylindrically shaped trunnion *d'*, formed integrally therewith and which projects laterally therefrom and is journaled in a bearing *c'* in the member *c* which extends entirely through said member, a cap *f* being secured by screws, or other suitable means, to the end of said trunnion *d*, to retain the trunnion in the bearing. Said member *c* is provided with an annular recess *c*²

about the bearing *c'* to receive a ring *e*, which is preferably of cast-iron and is cut transversely, so that the opposite portions thereof are resilient and adapted to be sprung apart to cause the same to bind against the surface of the annular recess *c*². Said ring is also adapted to fit on the trunnion *d'*, to provide an additional support therefor, when the parts are in locked position, as hereinafter described. The end 65 faces *e'* on the ring *e*, formed by slotting the same transversely, are formed to extend convergently from one side to the other, and a key *g* is arranged in a diametrically disposed slot *d*² in the trunnion *d'*, and is 70 mounted at one end to swing on a pivot *h* supported by said trunnion at one side of the axial line thereof. The opposite end of said key extends beyond the periphery of the trunnion into the transverse slot of the 75 ring *e* between the faces *e'*, preventing relative rotation of said ring and trunnion, and the sides of said key are tapered to correspond to the taper of said faces.

A pin *i* is mounted in the plate *f* and has 80 a spring *j* thereon, said pin extending into a recess *g'* in the key *g*, and the spring *j* bearing against said key, so that it tends to swing the key out of engagement with faces *e'*. A thumb-screw *k* is threaded into 85 the swinging member *d* in an oblique direction, and is adapted to bear on a correspondingly obliquely disposed face *g*² on the end of the key *g* opposite the pivot *e*, in position to force the same toward the point of 90 intersection of the planes of the faces *e'*.

The members having been placed in position, the manner of locking the member *d* from swinging is as follows:—After the shield has been adjusted to the desired position, the thumb-screw *k* is screwed inwardly into engagement with the face *g*², and the key *g* is caused to swing forwardly, so that it is firmly wedged between the tapering faces *e'* of the ring *e*, forcing said 100 faces apart and thus causing the ring *e* to spread and its outer surface to bear firmly against the surface of the annular recess *c*², so that the parts are all firmly locked together.

If it is desired to unlock the parts it is merely necessary to unscrew the thumb-screw *k* permitting the spring *j* to force the key *g* out of engagement with the ring *e*, so that the latter is permitted to contract 110

and thus become disengaged from the member *c*, thereby permitting the member *d* to swing readily with relation thereto.

While it would be within the range of mechanical equivalency to reverse the relation of the locking devices to the fixed and swinging members, I wish it to be understood that my invention is not especially limited to either arrangement, yet the particular arrangement shown is preferable, as, by it, I find it much more convenient to locate the thumb-screw in the swinging member and I avoid the objection of having it extend beyond the side of the shield support.

I claim:

1. A hinge support comprising a fixed member, a movable member having a longitudinally slotted trunnion extending into said fixed member, a transversely slotted expansion ring surrounding said trunnion and journaled in said fixed member, a key mounted in the slot of said trunnion and extending longitudinally into the slot of said ring to prevent relative rotation thereof, the sides of said key being extended convergently and means to move said key transversely to wedge the ends of the ring apart, and expand the ring into locking engagement with said fixed member.

2. A hinge support comprising a fixed member, a movable member having a trunnion extending into said fixed member, a transversely slotted expansion ring surrounding said trunnion and held in peripheral engagement with said fixed member, a transversely tapering key mounted in said trunnion and extending longitudinally into the slot of said ring to prevent relative rotation thereof, the slot of said ring being arranged to form transversely converging faces, and means to move said key transversely between said faces to wedge them apart and expand the ring into locking engagement with said fixed member.

3. A hinge support comprising a fixed member, a movable member having a trunnion extending into said fixed member, said trunnion having a radially disposed, longitudinally extending slot therein, an expansion ring having a transverse slot forming end faces, said ring encircling said trunnion and arranged in peripheral engagement with said fixed member, a wedging key disposed in the slot of said trunnion and extending longitudinally into the slot of said ring to prevent relative rotation thereof, and means to move said key transversely to force apart the end faces of said ring and expand the same into locking engagement with said fixed member.

4. A hinged support comprising a fixed member, a movable member having a trunnion extending into said fixed member, said trunnion having a radially disposed slot

therein, an expansion ring having a transverse slot forming end faces, said ring encircling said trunnion and arranged in peripheral engagement with said fixed member, a wedging key pivotally mounted in the slot of said trunnion and extending into the slot of said ring and means to swing said key on its pivot, to wedge apart the end faces of said ring to expand the same into locking engagement with said fixed member.

5. A hinge support comprising a fixed member, a movable member having a trunnion extending into said fixed member, said trunnion having a radially disposed slot therein, an expansion ring having a transverse slot forming end faces, said ring encircling said trunnion and arranged in peripheral engagement with said fixed member, a wedging key disposed in the slot of said trunnion and extending longitudinally into the slot of said ring to prevent relative rotation thereof, and a screw, threaded in said movable member and arranged to engage one side of said key and move the same transversely to wedge apart said end faces and expand said ring into locking engagement with said fixed member.

6. A hinge support comprising a fixed member, a movable member having a trunnion extending into said fixed member, said trunnion having a radially disposed slot therein, an expansion ring having a transverse slot forming end faces, said ring encircling said trunnion and arranged in peripheral engagement with said fixed member, a wedging key pivotally mounted in the slot of said trunnion and extending into the slot of said ring, and a screw, threaded in said movable member, in position to engage said key adjacent its free end, and swing the same on its pivot, to wedge said end faces apart.

7. A hinge support comprising a fixed member, a movable member having a trunnion extending into said fixed member, said trunnion having a radially disposed slot therein, an expansion ring having a transverse slot forming end faces, said ring encircling said trunnion and arranged in peripheral engagement with said fixed member, a wedging key pivotally mounted in the slot of said trunnion and extending into the slot of said ring, and a screw disposed in said movable member obliquely to the axis of the trunnion in position to swing said key laterally to wedge apart the end faces of said ring.

8. A hinge support comprising a fixed member, a movable member having a trunnion extending into said fixed member, said trunnion having a radially disposed slot therein, an expansion ring having a transverse slot forming end faces, said ring encircling said trunnion and arranged in peripheral engagement with said fixed mem-

ber, a wedging key disposed in the slot of said trunnion and extending into the slot of said ring to prevent relative rotation thereof, means to move the key laterally in one direction to wedge apart said faces and expand the ring and a spring arranged to engage said key to move it in the opposite direction to permit said ring to contract.

9. A hinge support comprising a fixed member, a movable member having a trunnion projecting from one side thereof and extending through said fixed member, means on the end of said trunnion to engage said fixed member to hold the trunnion against longitudinal movement therein, a transversely slotted expansion ring, mounted on said trunnion and journaled in said fixed member, a wedging key mounted in said trunnion and extending into the slot of said ring to prevent relative rotation of said ring and trunnion, means to move said key in one direction to wedge apart the ends of said ring and expand it in locking engagement with said fixed member, and a spring 20 to move said key in the opposite direction when released.

10. A hinge support comprising a fixed member having an aperture extending therethrough, said aperture being chambered at one end, to form an annular recess, a transversely slotted expansion ring arranged in said recess and having its bore of substantially the diameter of the unchambered portion of said aperture, a movable member having a radially slotted trunnion fitting 30 said aperture and the bore of said ring, a wedging key arranged in the slot of said trunnion and extending into the slot of said ring, means to move said key to expand said ring into locking engagement with said 40 fixed member, and a cap on the end of said trunnion arranged to engage the opposite side of said fixed member from said movable member.

In testimony whereof, I have signed my 45 name to this specification in the presence of two subscribing witnesses.

WILLIAM MILLER.
